no connection to Hollywood, and a reputation for dramatic penny-pinching. We had no idea what was going to happen when they took over, but we knew that nothing we were used to would remain the same.

The deal closed in January 1986. Shortly afterward, Tom and Dan held a corporate retreat in Phoenix. I didn't rank high enough to get invited, but I heard plenty of complaints and snickering from other ABC execs in the aftermath, about corny team-building exercises and Tom and Dan's homespun values. I'd later realize we were all being cynics and snobs. Over the next few years, those zany auditions would help form a unique camaraderie within the company, and Tom and Dan's unique vision would help define the network's identity.
